UNITED STATES PATENT OFFICE

ANDREW THOMA, OF CAMBRIDGE, MASSACHUSETTS, ASSIGNOR TO NORTH AMERICAN CHEMICAL COMPANY, OF CAMBRIDGE, MASSACHUSETTS, A CORPORATION OF MASSACHUSETTS

TEMPLATE SHOE FILLING APPARATUS

Application filed August 16, 1929. Serial No. 386,338.

My invention is a machine for filling shoes and relates to the filling of shoe-bottoms with plastic filler of the kind which is deposited and spread in the shoe-bottom cavity by hand 5 or tool or spatula resembling a trowel. While this machine is intended for handling any of the known kinds of commercial, spreadable filler, hot or cold, such as those disclosed in my numerous filler patents, it is especially 10 adapted to handle cold plastic filler, particularly of the dispersed binder kind both cold and hot dispersion and other plastic fillers somewhat analogous thereto which, as well known, are quite difficult to manage 15 properly because of their free flowing character which is lost quickly because of the rapid evaporation. On account of the difficulties as to evaporation etc. and also because of the growing requirements of modern 20 practice for continual increase in speed of filling shoes, my invention has for a further object the facilitating of speed in filling shoes. It also promotes neatness and economy. In case of highly evaporable fillers it 25 reduces to a minimum the loss by evaporation.

Using the last mentioned type of filler for purposes of illustration, the machine in its simplest embodiment consists of a conditioning chamber for holding and tempering or 30 maintaining in proper temper the desired bulk or mass of the loose filler, and working shelf or table for receiving segregated portions of the filler from said chamber in amounts only enough each time for a single 35 shoe or at the most for two or three or a few shoes. This table or shelf is in the form of a templet having one or more openings for delivering the filler into the shoe bottom cavity. The templet and the shoe bottom cavity 40 are maintained relatively stationary while the filler is deposited therein in predetermined sheet form. This constitutes one of the main features of my invention. Another main feature of my invention is providing 45 means for determining the shape, thickness and amount of the filler mass to be deposited in said cavity and for so maintaining the same until actually deposited in the cavity. Also in the preferred embodiment of my in- 50 vention one of the radically new features is

the provision of means for automatically pre-determining the amount of filler for the shoe bottom cavity and delivering said amount thereinto. In other words, although handling soft fluid filler, my machine determines the shape and then maintains said shape of the filler mass until actually in the shoe in properly deposited position, also it similarly determines the amount deposited, determines the 55 shape and thickness, and likewise it delivers this soft and ordinary unmanageable filler into the shoe as a sheet-like layer. In each of the foregoing respects my present invention is broadly new. Preferably the templet is made of spring material normally curved 60 slightly downward so that when the operator places an upturned shoe-bottom (on the last) against the underside thereof with the bottom cavity aligned with the filler delivery opening and presses the shoe-bottom upward, the spring templet will yield until it conforms exactly to the reverse curvature of the shoe-bottom, and, because of its spring 65 character, will press down in tight, close contact with the shoe-bottom all around the 70 bottom cavity of the shoe. Most shoes have slight curvature, being almost flat, whereas other shoes have considerable curvature, and this spring-like yielding table with its delivery orifice causes the instant automatic, 75 tight adjustment of the delivery orifice all around the cavity which is to be filled. Having placed the shoe-bottom (on its last, of course) thus in position the operator with his 80 hand tool or spatula slides a small heap of 85 filler from the chamber or from the ledge forward and wipes it into the shoe-bottom cavity through the opening and with a single sweep of the tool or knife levels it even with the top surface of the templet around the edge 90 of the opening. The thickness of the edge of the opening determines the amount of 95 filler deposited in the shoe-bottom and determines its height above the top level of the boundary of the shoe-bottom cavity. As it is impracticable and in fact impossible to make the opening correspond to the exact 100 shape and size of all the cavities of all the shoes, because no two shoes are precisely alike in this respect, I make the opening definitely

smaller and then depend upon the thickness of the templet at the edge of the opening to determine the surplus filler or additional height of the smaller deposited layer which 5 is necessary for the subsequent spreading of the plastic filler in order fully and correctly or exactly to occupy the entire cavity in proper relation to the outsole whenever laid.

To facilitate the positioning of the shoe 10 with relation to the filling table or delivery templet, a positioning support, preferably a roller, is provided for supporting the toe of the shoe, preferably yieldingly, so as to permit the operator to place the toe thereon 15 readily and then tip the shoe and its last upward endwise on the toe as a fulcrum until the filler opening and bottom cavity have been brought into the exact juxtaposition desired. If desired this filler delivery opening or ori-

20 fice of the templet is made adjustable for different sizes of shoes and shapes of bottoms. My invention however is primarily intended for the filling of McKay shoes and as only about three different sizes of filler delivery 25 openings are required for this kind of shoe, I prefer to provide the table or templet with the three separate openings.

As already stated, my invention is broadly new and accordingly it is capable of a wide 30 range of embodiments, two being herein presented to illustrate the carrying out of the invention in a more automatic manner and in a more rapid manner. Instead of the spatula or other hand tool I provide in one embodiment a rotary tool, power driven, and in another embodiment a reciprocating tool 35 preferably under the control of the operator. It will be understood that all the embodiments herein shown are illustrative, to make 40 clear the broad scope and radical advance of this invention.

Fig. 1 shows the machine in central transverse vertical section;

Fig. 2 is a top plan view of the table or 45 filler delivery-member or templet presenting by way of illustration and diagrammatically a single table with three openings as needed for McKay shoes for example;

Fig. 3 is a detail in top plan of an adjustable arrangement whereby a single opening 50 may be used for a considerable variation of sizes of shoes;

Fig. 4 is a cross section detail on the line 4—4 Fig. 3;

Fig. 5 is a detail in front elevation partly 55 broken away of the spring mounted toe supporting roller;

Fig. 6 is a perspective view of the hand trowel or filling tool or spatula;

Fig. 7 is a sectional view through the fore-part of a shoe on its last, illustrating certain 60 features of my invention in use;

Figs. 8-14 show a further or rotary embodiment of the invention, Fig. 8 thereof is 65 a central vertical section similar to Fig. 1

showing a power driven rotary applying mechanism;

Fig. 9 is a top plan view thereof partly broken away and in section;

Figs. 13 and 14 are enlarged sectional views 75 of a cam control;

Figs. 15-17 show a still further or reciprocating embodiment of the invention, Fig. 15 thereof illustrating the same in top plan view partly broken away;

Fig. 16 is a vertical longitudinal section on the line 16—16 of Fig. 15; and

Fig. 17 is a front elevation of the parts shown in Fig. 15 partly sectioned and broken away.

The conditioning chamber 1 may have the general shape shown in my Patent 957,393 dated May 10, 1910 excepting that it has a heavy top 2 for keeping the top of the chamber 1 continually sealed, (except for filling or loading with filler) and is provided with a stop 3 adjacent the hinge pivot 4 for preventing the operator from accidentally leaving the top open. At the lower front end of the chamber is an opening 5 which may be 95 closed by a slide door 6 working in guides 7 as the door or regulating valve 6 is raised or lowered by the operator by means of a handle 8. At the forward edge of a ledge 9 and extending therefrom to a supporting frame 10 I provide a member 11, preferably of yielding or spring sheet material, which constitutes the templet mentioned, shown in top plan view in Fig. 2 as provided with three delivery orifices 12, 13, 14, respectively, of different sizes conforming somewhat to the approximate shapes of shoe cavities. If the filler being used requires heat the templet is made of metal so as to retain some of the heat, but if restricted to cold filler it may be 100 made of transparent material such as celluloid, thereby further facilitating speed by enabling the operator to see how he is positioning the shoe. The spring templet 11 is preferably mounted in a slotted frame 10 extended at its ends 15 from the ledge 9. This rigid strong construction is necessary for proper strength and also advisable for conveying and storing moderate heat in case the machine is built for hot filler. Mounted below the ledge 9 are toe rests or supports in the form of rollers 16, 17, 18 which constitute fulcrums and also guiding and shoe-positioning members. These rollers are preferable instead of more stationary supports because 110 it is necessary not to mar the more or less delicate leather of the toe of the shoes being filled and therefore the rolling movement of a roller is preferable. Also the rollers preferably have soft coverings 19 of rubber, 115

120

125

130

cloth, leather or the like and are mounted on end bearings 20 and give limited vertical movement on posts 21 by means of springs 22 which tend normally to maintain them in upward position and yet permit downward yielding whenever required by the particular style or spring of the shoe. Preferably each roller has a hollow or directing and centering curve 23 for automatically bringing the toe 5 into alignment with the opening thereby aiding the operator in the proper positioning of the shoe-bottom beneath its filler opening. In Fig. 6 I have indicated conventionally a laying tool or spatula comprising a blade 24, handle 25 and offset neck 26, the latter being offset so as to permit the operator more conveniently to move the blade 24 flat over the templet 11 at any given opening without danger of bringing his hand which grasps the 10 handle too close to the templet. This is necessary in case a hot filler is used and therefore the templet is hot. I have indicated this spatula as electrically heated, conductor wires 27 indicated as in my Patents 878,688 15 of February 11, 1908 and 957,393 of May 10, 20 1910.

In case it is preferred to use an adjustable templet opening instead of having a templet provided with several fixed openings as 25 shown in Fig. 2, I provide the same in any convenient manner, as for example shown in Figs. 3 and 4. The opening 28 is provided by four blades or separate portions 29, 30, 31, 32 of the templet. Each blade is shown 30 as overlapping at one end the next blade so as to make a closed peripheral opening 28 to prevent any filler going through the templet at any place except the opening 28. The four movable plates are held adjustably in a 35 grooved frame 33. Thus if a larger opening 28 is desired, the operator separates the plates by pressing outwardly at the opposite longitudinal middle edges which causes the plates 29 and 30 to pivot or swing on each 40 other at their meeting points 34.

Before explaining the other embodiments of my invention, I will set forth the use of the more simple apparatus just described. The operator raises the heavy top 2 of the chamber 1 and dumps into the latter a quantity of the filler, the highly volatile or evaporable and changeable filler, let it be supposed. The heavy top falls and seals in the mass of filler against rapid evaporation or change. 50 He then raises the door or closing device 6 sufficiently to permit him to poke out onto the ledge 9 by means of his spatula 24 such amount of filler as he desires. He now takes a shoe, on its last, from the rack and quickly 55 places it bottomside up with the toe on the readily turning positioning-roll 16 and slides the same forward until it is properly beneath the opening 12 for example, and at once raises the shoe-bottom forcibly upward 60 in contact with the spring templet until the

latter is level or bent upward still further to fit the curve of the upturned shoe-bottom. The skilled operator accomplishes all this by the single forward thrust of the shoe in his left hand. He simultaneously places the toe 70 on the roll 16 as a support and fulcrum and raises the heel and thereby swings the shoe-bottom forcibly upward against the spring bottom or templet 11 until the latter has conformed itself into close peripheral engagement with the inturned edges of the upper, leaving the filler delivery opening 12 properly centered with the bottom cavity of the shoe. Then with his trowel he slides forward over the templet a proper amount of the plastic filler, thereby filling the opening and simultaneously with the same sweep of his tool levelling the filler accurately in the bottom cavity. This is accomplished by the 75 sliding sweep of the spatula blade 24 over the opening 12 in contact with the edges thereof. The operator judges from the size of the shoe-bottom cavity and the shape and depth thereof whether to use the large opening 12 or the small opening 14 or the intermediate opening 13. The edge thickness of the opening determines the height of the filler layer as deposited and left in the shoe-bottom at this stage of the operation. This 80 is important as it determines automatically the amount of filler deposited, or measures, as it were, the requirements of the shoe. Heretofore it has usually been the case that the operator, without any such regulating mechanism, would either get too much filler 85 into the cavity thereby necessitating brushing it off from the shoe and therefore soiling the adjacent parts of the shoe, or else he would not deposit quite enough filler in the shoe-bottom cavity. In the latter case a careless operator would leave the cavity improperly filled or the more careful operator 90 would be delayed by having to pick up the needed further amount of filler and place it in the shoe-bottom. Having thus delivered the exact amount of filler into the shoe-bottom cavity as determined automatically by the opening 12 and the method of use explained, and levelled the same as a true and exact sheet-like layer by the single sweep of his spatula as stated, the operator withdraws the shoe and either runs it under a usual spreading roll or accomplishes the same spreading by a further stroke of his 95 spatula blade 24 over the shoe-bottom, thereby spreading down to the level of the in-turned upper and outward into filling relation with the entire cavity, the layer of filler as previously left projecting by the templet opening 12. This will all be more readily 100 understood by viewing Fig. 7 where a shoe upper 35 is shown on its last 36 with its in-turned edges 37 forming a usual bottom cavity 38 in the middle of which is shown a deposited layer 39 of filler resting on the inner- 105 110 115 120 125 130

sole 40 and whose lateral size is determined by the edges of the opening 12 in the templet 11 and whose height above the depth of the cavity 38 is determined by the thickness of 5 the templet 11 at said edges. The operator's spatula blade 24 has swept the filler into the form of a sheet-like layer 39 exactly level with the top surface of the templet 11. When therefore the shoe and its last are withdrawn 10 this upstanding or projecting layer 39 is brought by a sweep of the operator's spatula blade 24 level with the inturned edges 37 of the upper and simultaneously spread laterally and in whatever direction required to 15 fill the bottom cavity 38 completely.

In Figs. 8-14, I have shown a rotary depositing mechanism. The table or templet support is shown as the bottom 41 of a shallow pan or holder 42 for the small amount 20 of filler withdrawn from the tank or supply reservoir 1 (small when the evaporable or rapidly changeable type of filler is being used) and mounted in this pan or filler holder is one or more movable members 43 herein shown as two, pivotally supported on trunnions 44 in a rotary post 45 journaled in a frame or spider 46 and rotated by any suitable means as by a pulley 47 and belt 48. These movable members or tools perform the 25 office of the spatula 24 for scraping or moving the soft mushy flowable filler quickly into the template opening and levelling it off the same as before explained. A templet 49 is shown having an opening 50 and an auxiliary toe rest 51, said opening being indicated in Fig. 8 as already filled with a layer 32 of the plastic filler. Preferably the depositing tool 43 is given substantially the same movement that the operator gives the 30 spatula 24. It not only slides the filler forward but presses it down into the opening 50 of the templet so as to make certain that the filler is not slid forward and more or less of it out again past the templet opening. This 35 flopping or swinging movement of the blade 43 may be accomplished in many ways, the means illustrated consisting of a triangular trip 53 fast on one end, shown in Fig. 8 as the outer end of each blade or filler mover 43 in position to engage fixed cams 54, 55 on the inner lower portion of the wall of the pan 42. As a blade 43 moves forward in the direction of the arrow 56 Figs. 9 and 11, its trip 53 is 40 in the position shown in Fig. 14. When it meets the rear end of the cam 54 the lower point or corner 57 (also see Figs. 13-14) strikes the adjacent end of the cam 54 and is thereby turned into the position shown in Fig. 13 so that its flat side 58 rides on the 45 top flat surface of said cam 54. This flops or tips over the blade 43 from its upright position into a slanting position and tends to press downward whatever mass of the loose filler has been shoved along ahead of 50 it as it rotated toward the templet opening.

Having filled and pressed down the filler (and with certain types of fillers compressed the same) so as to fully fill and level off the templet cavity the now upper end 59 strikes the cam 55 which operates to turn the blade 70 back again to its upright position in which position it is maintained by the flat surface 60 as it moves forward. It will be understood that the blade may be fixed in the carrier post 45 and thereby maintained continuously in the position shown in Fig. 11 but I prefer to have it capable of giving a slightly pressing movement on the filler at the moment of levelling the same into the templet opening. This tends to condense 75 and entirely fill the opening to its full capacity. As the shoe filling operative relieves the pressure on the auxiliary toe rest 51 the templet 49 slides rearwardly toward said operative and the front of the machine in its 80 ways 61, being actuated by any convenient means, herein shown as actuated by a weight 62 whose cord 63 is secured at 64 to a stationary part, said cord passing over a pulley 65 mounted in the far end of a slide plate 85 or bottom closure 66 which abuts against the forward end 67 of the templet plate 49, so as to move with the latter. Thus when the shoe is withdrawn and thereby the templet moves to the left from its position in Fig. 8 90 the space in the bottom of the pan which had previously been occupied by the open portion 50 of the templet is closed automatically by the closing plate 66 as shown in Fig. 9.

In Fig. 15 I have shown an embodiment of my invention in which the operation of the filler-depositing mechanism is reciprocal instead of rotary as last described. Projecting forward from the tank 1 is a bottom or 100 table 68 provided with a templet 69 in line with the filler delivery opening 5 and door 6 the same as in the previous constructions, sides 70 and wings 71 being preferably provided for holding the filler which the operator pokes out from the tank. A depositing 105 and levelling tool 72 is mounted on a carrier 73 operated by any suitable means, herein shown as a handle 74 to swing back and forth over the templet opening 75 in the templet 69. Said levelling tool may be of any convenient 110 shape, herein shown as flat on its underside to cover the opening 75 and slanting therefrom at 76, 77, for pressing the filler downward in the same way that a hand spatula is used. For poking the filler forward into the opening 75 and in position for the levelling tool to spread and press the same into said opening and level it off, I provide side wings, 115 scrapers, or filler movers 78, 79 movable with the carrier 73 and tool 72. Preferably wings 80 project laterally outward from said scrapers or filler movers to prevent the possibility of any filler dropping from the tank 120 behind one or the other of the scrapers or 125

filler movers when the latter are moved inwardly toward or past the opening 75. These scrapers 78, 79, the levelling tool 72 and the carrier 73 are mounted to swing from the 5 pivot 81, and the tool 72 preferably has a raised top side with downwardly slanting walls 82. As already stated the kind of 10 filler for which my apparatus is primarily intended is cold filler i. e. filler applied cold, but it may be applied hot, and so I have indicated at 83 heating means for the applying tool to prevent the filler from sticking there- 15 to and to speed up the relative movement and to maintain the filler properly melted or fluid for quick delivery. These walls 82 cooperate 20 with the wings 71 to form a sort of hopper for the filler as the latter is poked by the shoe filler workman from the tank into the work basin or onto the table 68. In use, the 25 operator pokes a small amount of filler from the tank onto the table 68, places the shoe bottom against the underside of the templet with the cavity properly aligned with the opening 75 and quickly swings the tool 72 and scrapers 78, 79, in one direction and then in 30 the other and the filling result has thereby been accomplished. For example he moves the handle 74 to the left, Figs. 15 and 17. The 35 scraper 79 immediately shoves a mass of the loose plastic filler over the opening 75 and some of it slightly to the left thereof, and then the operator swings the mechanism quickly to the right. The inclined wall 77 presses the filler down into the opening 75 and the flat bottom of the tool levels the same 40 accurately. The operator stops the tool in the position shown in Fig. 17, removes the shoe and replaces it with another. He then repeats the movements and thereby fills the 45 second shoe. If he has any doubt about the templet opening being properly filled he gives the parts a further swing to the right and back to the left. The swinging movement is accomplished with considerable speed.

It will be understood that I have not undertaken to show all the minute details but simply to show sufficient embodiment of the invention to make it clearly understood and 50 to show its broad character. All the templets may be adjustable as shown in Fig. 3 and the templet is preferably always slightly springy, the same being exaggerated in Fig. 1 to bring out the function more clearly. 55 The chief object of this invention is to increase the speed of filling shoes by providing means for definitely limiting and determining the amount of filler delivered to the shoe-bottom and restricting or requiring the 60 delivery into the shoe-bottom cavity of said measured amount of filler, preferably in the form of a level layer, in a predetermined shape and position conforming preferably to the approximate shape of the shoe-bottom cavity. All the operator has to do is to push

the shoe, on its last, into position and fill the cavity through the opening in the templet by one levelling sweep of the spatula 24 or blade 43 or tool 72 or other depositing means, as the case may be. The templet defines and determines the amount as well as the shape and thickness of filler to be deposited in the shoe-bottom cavity, directs and guides the filler directly, neatly and correctly into the cavity, and maintains the same in form, dimensions and amount until actually deposited in the cavity. The subsequent spreading of the filler in the shoe bottom cavity is the same in my present invention as in previous practice excepting that here the amount of 70 filler is more correctly measured and hence the spreading and final filling are accurate and free from danger of undersupply or of oversupply and of waste or soiling of the shoe, and the operation is quicker, easier and 75 requires no skill.

My invention is capable of a wide range of variations and substitutions, as will be understood by those skilled in the art, and is not limited excepting as defined in the following claims.

I claim:

1. A machine for filling shoe bottom cavities comprising a templet adapted and arranged to receive the bottom of a shoe against its under side, and a container for plastic filler having an outlet for depositing the filler on the upper side of the templet, said templet having an opening conforming approximately to the size and shape of the cavity to be filled and constituting means for restricting the filler delivered therethrough to a predetermined shape within the periphery of the shoe bottom cavity, and said templet also having an unobstructed top surface adjacent said opening adapted to cooperate with a leveling sweep of a spreading tool across the opening.

2. A machine for filling shoe bottom cavities comprising a templet adapted and arranged to receive the bottom of a shoe against its under side, and a container for plastic filler having an outlet for depositing the filler on the upper side of the templet, said templet having an opening of less area than the area of the cavity to be filled and constituting means for restricting the filler delivered therethrough to a predetermined quantity within the periphery of the shoe bottom cavity, and said templet also having an unobstructed top surface adjacent said opening adapted to cooperate with a leveling sweep of a spreading tool across the opening.

3. A machine for filling shoe bottom cavities comprising a templet adapted and arranged to receive the bottom of a shoe against its under side, and a container for plastic filler having an outlet for depositing the filler on the upper side of the templet, said templet having an opening smaller than the

cavity to be filled and so proportioned in size to the thickness of the templet that the volume of filler laid through the opening into the shoe bottom cavity and levelled off at the top side of the templet is substantially equal to the filler requirement of the cavity, and said templet also having an unobstructed top surface adjacent said opening adapted to cooperate with a leveling sweep of a spreading tool across the opening.

4. A machine for filling shoe bottom cavities comprising a templet having an opening of less area than the area of the cavity to be filled and constituting means for restricting the filler delivered therethrough to a predetermined quantity within the periphery of the shoe bottom cavity, said templet being made of resilient material adapted to conform to the bottom shape of the shoe bottom when the latter is pressed against its under side, and a container for plastic filler having an outlet for depositing the filler on the upper side of the templet.

5. A machine for filling shoe bottom cavities comprising a templet having an opening of less area than the area of the cavity to be filled and constituting means for restricting the filler delivered therethrough to a predetermined quantity within the periphery of the shoe bottom cavity, said templet being made of resilient sheet metal adapted to conform to the shape of the shoe bottom when the latter is pressed against its under side, and a container for plastic filler having an outlet for depositing the filler on the upper side of the templet.

6. A machine for filling shoe bottom cavities comprising a templet having an opening of less area than the area of the cavity to be filled and constituting means for restricting the filler delivered therethrough to a predetermined quantity within the periphery of the shoe bottom cavity, said templet being made of resilient sheet metal normally curved downward and adapted to conform to the shape of the shoe bottom when the latter is pressed against its under side, and a container for plastic filler having an outlet for depositing the filler on the upper side of the templet.

7. A machine for filling shoe bottom cavities comprising a templet having an opening to determine the quantity of filler to be delivered therethrough into the shoe bottom cavity, and means for holding a shoe stationary beneath the templet, said means including a downwardly yielding shoe support below the templet adapted to cause the shoe bottom cavity to register with the opening in the templet when the shoe bottom is pressed against the under side of the templet.

8. A machine for filling shoe bottom cavities comprising a templet having an opening to determine the quantity of filler to be delivered therethrough into the shoe bottom

cavity, and a yielding roller having a grooved and padded surface below the templet, adapted to support the toe of a shoe to facilitate the registration of the shoe bottom cavity with the opening in the templet when the shoe bottom is pressed against the under side of the templet.

9. In a machine for filling shoe-bottom cavities, means for depositing fluid, plastic filler in predetermined sheet form in a shoe-bottom cavity and cooperating means for supporting the shoe-bottom cavity substantially stationary to receive said deposit in said predetermined sheet form.

10. In a machine for filling shoe-bottom cavities, means for depositing fluid, plastic filler in predetermined sheet form in a shoe-bottom cavity, said filler depositing means comprising a delivery orifice having a contour conforming approximately to the shape of the cavity, and cooperating means for positioning the shoe-bottom cavity to receive said deposit in said predetermined sheet form.

11. In a machine for filling shoe-bottom cavities, means for depositing fluid, plastic filler in predetermined sheet form in a shoe-bottom cavity, said filler depositing means comprising a delivery orifice, and cooperating means for positioning the shoe-bottom cavity stationary with relation to said orifice to receive said deposit in said predetermined sheet form.

12. A machine for filling shoe bottom cavities comprising a templet adapted and arranged to receive the bottom of a shoe against its under side, said templet having an opening conforming approximately to the size and shape of the cavity to be filled and constituting means for restricting the filler delivered therethrough to a predetermined shape within the periphery of the shoe bottom cavity, a spreading tool above the templet and means for imparting to the spreading tool a sweeping movement across said opening to deposit a layer of filler of predetermined thickness through the opening and into the shoe bottom cavity.

13. A machine for filling shoe bottom cavities comprising a templet adapted and arranged to receive the bottom of a shoe against its under side, said templet having an opening conforming approximately to the size and shape of the cavity to be filled and constituting means for restricting the filler delivered therethrough to a predetermined shape within the periphery of the shoe bottom cavity, a rotary frame journaled above the templet, and a spreading tool carried by the frame and positioned to make a sweeping movement across said opening when the frame is turned on its axis.

14. A machine for filling shoe bottom cavities comprising a templet having an opening conforming approximately to the shape of

the cavity to be filled, the area of the opening being less than the area of the cavity so that plastic filler delivered through said opening is restricted to a predetermined shape within the periphery of the cavity, and means for supporting a shoe bottom against the under side of the templet and beneath the templet opening, whereby the plastic filler deposited in the cavity through said opening may be leveled to a predetermined thickness and sheet-like form by wiping a spreading tool over the upper face of the templet across said opening.

15. A machine for filling shoe bottom cavities comprising a templet having an opening conforming approximately to the shape of the cavity to be filled, the area of the opening being less than the area of the cavity so that plastic filler delivered through said opening is restricted to a predetermined shape within the periphery of the cavity, means for supporting a shoe bottom in stationary position against the under side of the templet with the cavity located beneath the templet opening, and means movable over the upper surface of the templet and across the opening for spreading the plastic filler through the opening into the cavity and leveling it flush with the upper surface of the templet.

16. A machine for filling shoe bottom cavities comprising a templet having an opening conforming approximately to the shape of the cavity to be filled, the area of the opening being less than the area of the cavity so that plastic filler delivered through said opening is restricted to a predetermined shape within the periphery of the cavity, means for supporting a shoe bottom in stationary position against the under side of the templet with the cavity located beneath the templet opening, and means movable over the upper surface of the templet and across the opening for spreading the plastic filler through the opening into the cavity and leveling it flush with the upper surface of the templet, said means comprising a rotatable frame having a spreading tool pivoted therein.

17. A machine for filling shoe bottom cavities comprising a templet having an opening conforming approximately to the shape of the cavity to be filled, the area of the opening being less than the area of the cavity so that plastic filler delivered through said opening is restricted to a predetermined shape within the periphery of the cavity, means for supporting a shoe bottom in stationary position against the under side of the templet with the cavity located beneath the templet opening, and means movable over the upper surface of the templet and across the opening for spreading the plastic filler through the opening into the cavity and

leveling it flush with the upper surface of the templet, said means comprising an oscillating frame provided with a leveling tool.

Signed by me at Cambridge, Massachusetts, this eighteenth day of July, 1929.
